UNITED STATES PATENT OFFICE.

JOHN A. HINGER, OF DETROIT, MICHIGAN.

RADIATOR.

1,233,472.

Specification of Letters Patent. Patented July 17, 1917.

Application filed October 23, 1916. Serial No. 127,547.

To all whom it may concern:

Be it known that I, JOHN A. HINGER, a citizen of the United States of America, residing at Detroit, in the county of Wayne and State of Michigan, have invented certain new and useful Improvements in Radiators, of which the following is a specification, reference being had therein to the accompanying drawings.

10 The invention relates to radiators of the type particularly designed for use in cooling of internal combustion engines, and it is the object of the invention to obtain an inexpensive and mechanically strong structure, 15 which is also highly efficient as a cooling agent.

In the drawings:

Figure 1 is a cross-section through a portion of a radiator constructed in accordance 20 with my invention;

Fig. 2 is a section showing the several sections separated.

In the construction of radiators the heat from the liquid circulating medium is first 25 transferred by conduction through the metallic walls of the conduit and is then dissipated by convection of air passing in contact with said walls or with radiating fins extended therefrom. It has been found that 30 the amount of surface required for the transfer of the heat from the liquid to the metal is much less than that required for transfer of the heat from the metal to the air, and consequently the efficiency of the 35 radiator is not decreased by a considerable reduction in the amount of liquid-contacting surface, providing that there is sufficient air-contacting surface in good heat conducting relation thereto. I have therefore sim-

40 plified and cheapened the construction of the radiator by reducing the number of water tubes and by providing radiating fins so fashioned as to maintain good heat-conducting relation with said tubes as well as to 45 mechanically reinforce and brace the structure. Furthermore, I have devised a construction which has the conventional appearance of a cellular radiator of the type in which each cell is surrounded by a water 50 passage. My improved construction is also one in which the elements of the structure may be readily formed from rolled sheet-metal and may be quickly assembled in relation to each other.

55 In detail, A A' are similar sheets of metal which have been crimped or fash-

ioned, preferably by passing through crimping rolls, into the zigzag form shown. These crimped sheets when placed adjacent to each other will form parallel walls of a zigzag 60 water tube, and the ends of the tubes may be readily connected to the tanks or headers by lateral extensions B of the parallel walls of adjacent tubes, which are seamed to each other as indicated at C. D is a fin strip 65 crimped to form portions E that are parallel to the crimped walls of the members A and A', said portions being alternately turned in opposite directions with intermediate connecting portions, F. The construction is 70 such that the crimped fin forms opposite side walls of air cells of hexagonal or other polygonal shape, which cells are completed on one side by the zigzag water tubes, with portions of the fin lying parallel to and in 75 contact with the walls of said tubes. The cells are completed upon the opposite side by an intermediate fin strip G of zigzag form similar to the members A and A', while a fin strip H bent to the reverse form of the 80 strip D is arranged between the strip G and the next adjacent water tube. Thus in the completed structure there will be two rows of polygonal air cells intermediate each pair of water tubes, said cells being formed 85 chiefly by the fin strips D, G and H, but completed by the walls of the water tubes and also having the fins of alternate cells in contact with the walls of the water tubes 90 for the transfer of heat from one strip to the other.

In assembling the structure the several crimped strips may be readily placed in proper relation to each other and by then dipping the edge portions in solder they will 95 be strongly united, with the joints in the water tubes completely sealed. It will be noted that all of the bends in the sheet-metal are obtuse angles, which may be made without overstressing the metal, thereby avoiding 100 danger of leaks. To complete the structure the tanks I and J are formed of sheet-metal and soldered or otherwise secured, as indicated at K.

What I claim as my invention is:

1. In a radiator section parallelly-arranged zigzag strips constituting a water tube, said strips respectively forming troughs at each side of the tube, a fin strip bent to have portions lying parallel and in 110 contact with the walls of alternate troughs at one side of said water tube and portions

forming complementary walls of air cells with the intermediate troughs on the same side of said water tube.

2. In a radiator section parallelly-arranged zigzag strips constituting a water tube, said strips respectively forming troughs at each side of the tube, a fin strip bent to have portions lying parallel to and in contact with the walls of alternate troughs at one side of said water tube with intermediate portions forming complementary walls of air cells with the intermediate troughs on the same side of said water tube, and a zigzag fin strip parallel to the walls of said water tube having alternate zigzags in contact with complementary walls of the air cells and intermediate zigzags forming complementary walls of intermediate air cells.
3. A radiator comprising parallelly-arranged zigzag strips constituting walls of adjacent water tubes, a fin strip bent to have portions lying parallel to and in contact with alternate zigzags of one of said water tubes, with intermediate portions forming complementary walls of air cells with the intermediate zigzags of said water tube

wall, a reversely-bent fin strip having a similar relation to the other water tube, and an intermediate zigzag strip having portions alternately in contact with and parallel to portions of said fin strips, and together therewith and said water tube walls completing two adjacent rows of air cells intermediate adjacent water tubes. 30

4. A radiator comprising parallelly-arranged zigzag strips constituting walls of adjacent water tubes, a fin strip bent to have portions parallel to and in contact with alternate zigzags of one of said water tube walls and intermediate portions forming 40 complementary walls of air cells with the intermediate zigzags of said water tube wall, a reversely-bent fin strip having a similar relation to the adjacent water tube wall, a zigzag strip parallel to the walls of said 45 water tubes arranged intermediate said fin strips and in contact with alternate portions thereof, and extensions of the walls of said water tubes seamed to each other and constituting a wall of a tank or header. 50

In testimony whereof I affix my signature.
JOHN A. HINGER.
